(57) CLAIM

The ornamental design for a glittered shoe with bow, as shown and described.

DESCRIPTION

FIG. 1 is a perspective view of a first embodiment of a design for a glittered shoe with bow.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a perspective view of a second embodiment of a design for a glittered shoe with bow.

FIG. 8 is a front view thereof.

FIG. 9 is a rear view thereof.

FIG. 10 is a left side view thereof.

FIG. 11 is a right side view thereof.

FIG. 12 is a top view thereof.

FIG. 13 is a perspective view of a third embodiment of a design for a glittered shoe with bow.

FIG. 14 is a front view thereof.

FIG. 15 is a rear view thereof.

FIG. 16 is a left side view thereof.

FIG. 17 is a right side view thereof; and,

FIG. 18 is a top view thereof.

The bottom of the shoe forms no part of the claimed design. Features shown in broken lines depict portions of the glittered shoe with bow that form no part of the claimed design.
